UNITED STATES PATENT OFFICE.

GERARD CRANE, OF NEW YORK, N. Y., ASSIGNOR TO BRADFORD WILLARD,
OF SAME PLACE.

WASH-PAD.

SPECIFICATION forming part of Letters Patent No. 269,182, dated December 19, 1882.

Application filed March 11, 1882. (No model.)

To all whom it may concern:

Be it known that I, GERARD CRANE, of the city, county, and State of New York, have invented certain Improvements in the Manufacture of Wash-Pads from Hair, of which the following is a specification.

This invention is based upon the discovery that "curled hair," so called, when placed in a mass and subjected to the rubbing action incident to the use of a wash-pad acquires a certain consistency combined with the power of absorbing and releasing liquids which render it a superior substitute for the ordinary flesh-brush and ordinary sponge for the purposes of the toilet.

The invention also comprises a novel method of treating the hair in order to increase its efficacy for the purpose indicated.

The drawings represent, in Figures 1 and 2, respectively, a transverse sectional view and a side view of a washing-pad composed of hair and made according to my said invention.

In the practice of my invention, I take ordinary "curled hair," so called, and bring the same into approximately the shape required for the pad—as, for example, an oblate spheroid of, say, three to four inches in its greatest diameter, or any size desired. In order to cause this to maintain its shape, I place it within a sack of substantially the form above indicated, and composed of muslin or any other loose or porous fabric, and preferably with an opening in one side, this covering being represented at B in the drawings, while the hair itself is shown at A, the opening aforesaid being indicated at a. As thus provided, the device may be used in the same manner as an ordinary sponge or flesh-brush for toilet purposes, and for a short time will require that the back or covering B be retained in order that the mass of hair may not lose its shape. After a short use, however, with water, soap, or any usual detergent, the hair mass works together by the adhesion of its fibers to an extent sufficient to insure the retention of its general form throughout all its subsequent use, whereupon the covering may be removed. My invention, constructed as aforesaid, provides not only a cheaper, but a more effective device for toilet purposes than the ordinary flesh-brush or the common sponge. I find,

however, that by subjecting the hair to certain preliminary treatment I obtain better results than with curled hair in its ordinary condition. In doing this, I first expel the moisture from the hair by heating it in a suitable oven at a temperature not exceeding, say, 212° Farenheit, and which may be as low as 80° or 90°. The lower the temperature the longer the period required for drying the hair; but this is a matter of mere judgment, inasmuch as it is only requisite to expel moisture from the hair and bring the same to a dry and crisp condition. When this is accomplished I provide a liquid composed of glycerine, commercial hartshorn, and borax in the following proportions: four quarts of glycerine, one quart of hartshorn, and one ounce of borax. I then take about forty pounds of the dried hair and immerse it in the liquid for a short time—say about three hours—after which the hair is removed, allowed to drain until no more of the liquid will drain off, and the hair is then dried by a gentle heat, and is ready for use, as hereinbefore explained. The hair thus prepared is found to be more pliable and to afford a finer lather when soap is rubbed upon it than is the case with the unprepared hair.

I do not claim a "bosom-pad," so called, composed of a fabric shell and a filling of hair, and of substantially concavo-convex form. Neither do I claim a mitten composed of horse-hair, formed into heavy cords or threads, and then woven into shape; but

What I claim as my invention is—

1. A washing-pad composed of curled hair the fibers of which are matted or intermingled and combined with an external back or covering having an opening, a, at one side, all substantially as and for the purpose herein set forth.

2. The herein-described method of preparing curled hair for use as a washing-pad by first drying the hair and then treating it with a compound of glycerine, commercial ammonia, and borax in about the proportions specified, substantially as and for the purpose herein set forth.

GERARD CRANE.
